CLAIM

We claim the ornamental design for a fuel briquet, as shown and described.

DESCRIPTION

FIG. 1 is a top perspective view of the first embodiment of a fuel briquet, showing our new design;

FIG. 2 is a right side elevation view thereof, the left side elevation view being the same;

FIG. 3 is a front elevation view thereof, the back elevation view being the same;

FIG. 4 is a top plan view thereof;

FIG. 5 is a top perspective view of the second embodiment of a fuel briquet, showing our new design;

FIG. 6 is a right side elevation view thereof, the left side elevation view being the same;

FIG. 7 is a front elevation view thereof, the back elevation view being the same; and,

FIG. 8 is a top plan view thereof.

The broken line denoting the bottom profile of the fuel briquet is for illustrative purposes only and forms no part of the claimed design.
